GUN LIMBER

Heinrich Herlach, Berlin-Frohnau, Germany, assignor to Rheinmetall-Borsig Aktiengesellschaft, Dusseldorf, Germany, a corporation of Germany

Application September 24, 1938, Serial No. 231,593
In Germany June 15, 1937

9 Claims. (Cl. 89—40)

This invention relates to transportable carriages or limbers for gun platforms and mountings, artillery control equipment, and other heavy loads, of the kind in which the carriage or limber 5 has a forked frame the limbs of which are supported on wheels for transport.

Gun mountings attachable to forked frame limbers are known in which the limbs of the forked frame constitute a coupling lever and can 10 also be used as lifting levers to raise the mounting, in which system the limber wheels have their axles journalled on spring-supported crank arms on a cross-beam of the limber, which beam alone sustains the axle load and relieves the limbs of 15 the fork frame therefrom.

The present invention provides an improvement in limber systems in which the fork frame limbs have the wheels directly mounted thereon and unconnected with each other. Such limbers have 20 the disadvantage that the fork frame is not sufficiently rigid during transport in loaded condition.

According to the present invention a stiffening of the limber frame in the loaded condition is 25 obtained by producing an elastic deformation of the limbs of the fork frame about their longitudinal axes. For this purpose stop members on the limber frame cooperate with load-raising means, such as windlasses on the limber frame, to produce the elastic deformation of the fork 30 limbs, secured by means of lashing members. The deformation of the fork limbs restores the toeing-in or splay of the wheels which the load itself would eliminate.

Examples of the invention illustrating this 35 method of deformation are shown in the accompanying drawings, in which:

Figure 1 shows a limber for a gun emplacement in longitudinal section.

Fig. 2 shows the limber in plan.

Fig. 3 is a section on the line X—Y of Fig. 1, the frame being unloaded.

Fig. 4 is a section on the line X—Y of Fig. 1 after the load has been hung on.

Fig. 5 is a section on the line X—Y of Fig. 1 after the warping of the limbs of the fork.

Fig. 6 is a section on the line X—Y of Fig. 1 after the load has been secured in place.

Fig. 7 shows the gun emplacement or platform in side elevation and partial section.

Fig. 8 shows the gun emplacement or platform in plan.

Fig. 9 shows the apparatus for raising and securing the load, in longitudinal section.

Fig. 10 shows in longitudinal section the sus-

pension of the load at the shank end of the fork frame.

Fig. 11 is a section on the line Z—U of Fig. 9, the frame being unloaded.

Fig. 12 is a section on the line Z—U of Fig. 9 after the load has been hung on.

Fig. 13 is a section on the line Z—U of Fig. 9 after the warping of the limbs of the fork.

Fig. 14 is a section on the line Z—U of Fig. 9 after the load has been secured in place.

Figs. 15 and 16 show two other embodiments of the invention in side elevation and partial section, respectively.

The platform *a*, (see Figs. 7 to 10 and 12 to 14) which forms the load to be carried by the limber, 15 has on both sides of its wide end hook bolts *a*₁ and at its narrow end a hook *a*₂. The limber (see Figs. 1 to 6 and 9 to 14) is a fork-shaped frame *b* having wheels *b*₁, a supporting bar *b*₂ in the shank member, and hoisting gear *c* on the 20 ends of the fork limbs. The hoisting gear *c* shown (Figs. 1, 2 and 9) consists of a chain wheel *c*₁ with a recess *c*₂ in its rim, chain *c*₃, worm gear *c*₄ of which the details are not shown, and a crank handle *c*₅.

Each limb of the limber frame *b* also carries at its end a coupling member *d* having inclined jaws. The jaws of the coupling members cooperate with hooks *d*₂ to engage the stems of the hook bolts *a*₁ on the platform *a*, which hooks *d*₂ are pivoted on the coupling members *d*. The coupling members *d* have inclined surfaces *d*₁ cooperating with stops *a*₃ on the platform, for the purpose of locating the latter relatively to the limber frame *b*. The hooks *d*₂ have handles provided with cams *d*₃ each of which cooperates with the recess *c*₂ in the respective chain wheel *c*₁. The hooks *d*₂ are locked in engaged and disengaged positions by means of lugs *c*₅ on the handles cooperating with notches in a block *c*₄ fixed on 40 the limber. Near the end of each limb of the limber frame a stop *e* projects inwards and downwards (Figs. 1, 2 and 11 to 14), whereby the fulcrum provided by the stop is laterally spaced from the line of pull of the windlass chain in the 45 bolt *a*₁.

The platform *a* is rendered mobile by means of the limber *b* in the following way:

After the shank bar *b*₂ of the limber has been run into the hook *a*₂ of the platform and the 50 windlass chains *c*₁ have been attached to the hook bolts *a*₁, the wide end of the platform *a* is hauled up by means of the windlasses *c* towards the limbs *b*. The wheels *b*₁, the original position of which is shown in Fig. 3, at first assumes the 55

position shown in Fig. 4 as the wheel frame bends under the load. On being hoisted further up, however, the platform *a* strikes against the stops *e* in the wheel fork *b* (Fig. 12). In this position 5 the supporting hook *d*₂ cannot yet be turned over into the "fast" position. The platform, as it is further hoisted, now presses against the stops *e* and the limbs of the wheel fork *b* are bent about their longitudinal axis (Figs. 5 and 13). The 10 supporting hook *d*₂ can now be rocked into the "fast" position and the windlasses *c* are allowed to run back slightly as far as the cams *d*₃ in the recesses *c*₂ (Fig. 9) will permit. In this way the 15 windlasses *c* and the chains *c*₃ are relieved of the load and the stems of the hook bolts *a*₁ rest in the supporting hooks *d*₂ (Fig. 14). The toe-in or splay of the wheel *b*₁, which is lost when the load is hung on, is thus restored (Fig. 6). As the 20 windlasses *c* are wound up, the stops *a*₃ of the platform *a* (Fig. 9) engage the inclined surfaces *d*₁ so that the platform is aligned also longitudinally between the inclined surfaces *d*₁ and the supporting bar *b*₂ of the limber.

The platform is unlimbered as follows: The 25 windlasses *c* are wound up until the supporting hooks *d*₂ can be disengaged (Fig. 13). After these hooks have been swung aside, the platform *a* is lowered by means of the windlasses *c*, the chains *c*₃ are unhooked from the hook bolts *a*₁ and the 30 bar *b*₂ is run out of the hook *a*₂.

The platform shown in Fig. 15 is substantially the same as that of the preceding example (Figs. 1 to 14). It has, in addition, lashing bolts *a*₄ for 35 retaining the transverse deformation of the fork limbs *b*. The latter have at their ends windlasses *c*, supporting hooks *d*₂, and, further inwards, the fulcrum stops *e*. At the shank end of the fork frame is the carrier bar *b*₂. When limbering up, the bar *b*₂ is run into the hook *a*₂, the chains *c*₃ 40 are hooked onto the hook bolts *a*₁ and the wide end of the platform is drawn towards the fork limbs *b* by the windlasses *c*. The stops *e* come into contact with the platform *a*. On further turning 45 of the windlasses the ends of the fork limbs bend elastically, as shown in a somewhat exaggerated manner in broken lines in Fig. 15. The supporting hook *d*₂ is then engaged with the lashing bolt *a*₄, and the windlass is allowed to run back slightly, so that the supporting hook *d*₂ takes 50 the load. To let the platform *a* down, the windlasses *c* must be wound up again, so that the supporting hook *d*₂ can be disengaged. The platform *a* is then let down by means of the wind- 55 lasses *c* as above.

The platform *a* shown in Fig. 16 has at its wide end on both sides carrier bolts *a*₅ and at its narrow end lashing bolts *a*₆. The limber fork *b* has a prolonged lever-like tail *b*₃ and at its open end 60 a gripper hook *b*₄, also further inwards fulcrum stops *e*, as in the preceding example. To limber up the platform *a*, the limber fork *b* is run over it in such a way that the gripper hooks *b*₄ engage the carrier bolts *a*₅. The tail *b*₃ is then depressed 65 and in this way the platform *a* is raised at its wide end, until it comes into contact with the stops *e*. The tail is then depressed further so that the limber fork *b* (as shown exaggerated in broken lines in Fig. 16) bends elastically until the 70 carrier hook *d*₄ can engage the lashing bolts *a*₆. In this case also the limber fork *b* is elastically deformed towards the platform *a* with the help of the stops *e*. It would, of course, be possible to 75 arrange the stops *e* in this example in a manner similar to that of the first example (Figs. 1 to

14) so that the limbs of the limber fork *b* are warped about their longitudinal axis.

The invention is also applicable to frames having a plurality of axles and to motor-driven vehicles with a fork-ended chassis or bogie.

The important point is that when the load is limbered up, the wheel fork shall be deformed in such a way that it is stressed by its own elasticity against the load. At the same time, of course, the stress so applied to the limber frame must 10 not exceed the maximum forces to which it is subjected when travelling over bad roads.

I claim:

1. A limber having a fork-shaped frame with 15 transport wheels independently mounted on the limbs of the fork and adapted to carry a load, comprising means for raising the load into transport position on the limber, means between said load and fork-shaped frame providing fulcrum contact which is transversely spaced from the 20 line of action of the load-raising means whereby the fork frame receives transverse elastic deformation during the raising of the load to transport position, and means for securing the load to the limber with the frame of the latter thus deformed. 25

2. A limber having a fork-shaped frame with 30 transport wheels independently mounted on the limbs of the fork and adapted to carry a load, comprising means for raising the load into transport position on the limber, means between said load and fork-shaped frame providing fulcrum contact which is transversely spaced from the 35 line of action of the load-raising means whereby the fork frame receives transverse elastic deformation during the raising of the load to transport position, and means comprising hook couplings for securing the load to the limber with the frame of the latter thus deformed. 35

3. A limber having a fork-shaped frame with 40 transport wheels independently mounted on the limbs of the fork and adapted to carry a load, comprising means on each limb of the fork-shaped frame for raising the load into transport position, a stop member on each of said limbs, 45 said stop members being arranged to engage the load before the complete raising of the latter at points laterally displaced from the points of engagement of the raising means with said load, whereby the fork frame receives a transverse 50 elastic deformation when the load is in transport position, and means for securing the load to the limber with the frame of the latter so deformed.

4. A limber according to claim 3, in which the 55 securing means comprise a coupling plate in each limb of the fork frame, said plate having jaws at its lower end, a hook pivoted to the coupling plate, and a bolt on the load arranged to enter said jaws and be held therein by said hook.

5. A limber having a fork-shaped frame with 60 transport wheels independently mounted on the limbs of the fork and adapted to carry a load, comprising means for raising the load into transport position on the limber; means between said 65 load and fork-shaped frame providing fulcrum contact which is transversely spaced from the line of action of the load-raising means whereby the fork frame receives transverse elastic deformation during the raising of the load to transport 70 position, means for securing the load to the limber with the frame of the latter thus deformed, and means for longitudinally aligning the load with each limb of the fork frame during the raising of the load to transport position. 75

6. A limber according to claim 5, in which the aligning means comprise inclined surfaces formed on the securing means and stops on the load cooperating with said surfaces.
- 5 7. A limber according to claim 3, in which a gun platform is provided having a wide end which is suspended from the fork limbs for transport, and a narrow end suspensible from the shank end of the fork frame.
- 10 8. A limber according to claim 3, in which the raising means comprise a windlass on each limb of the fork frame.
9. A limber having a fork-shaped frame with transport wheels independently mounted on the 15 limbs of the fork and adapted to carry a load, comprising an extension of the shank end of the
- fork-shaped frame forming a lifting lever for the load, a platform for the load, means comprising cooperating parts on said platform and limbs for suspending the platform from the limber frame, said parts being interengageable by tilting the limber frame on its wheels over the platform while the latter is on the ground, fulcrum stops operative between said limbs and said platform at points spaced from said suspending means, and securing means including cooperating members 10 on said platform and fork frame located near the shank end of the latter, said members being interengageable only when the fork limbs have been elastically deformed by action on said lifting lever. 15

HEINRICH HERLACH.
